UNITED STATES PATENT OFFICE.

SAMUEL H. CASSELBERRY, OF COLLEGEVILLE, PENNSYLVANIA, ASSIGNOR
OF ONE-HALF TO WILLIAM PRIZER, OF SAME PLACE.

ROLLING WINDOW-SCREEN.

SPECIFICATION forming part of Letters Patent No. 566,284, dated August 18, 1896.

Application filed March 19, 1896. Serial No. 583,931. (No model.)

To all whom it may concern:

Be it known that I, SAMUEL H. CASSELBERRY, a citizen of the United States, residing at Collegeville, in the county of Montgomery and State of Pennsylvania, have invented certain new and useful Improvements in Rolling Window-Screens; and I do hereby declare that the following is a full, clear, and exact description of the invention, which will enable others skilled in the art to which it appertains to make and use the same.

This invention relates to that class of rolling window-screens which embody a screen fabric mounted upon a spring-roller and adapted to be detachably connected with the sliding sash.

The object of my invention is to provide a simple and improved screen of this character in which the edges of the screen fabric will be more securely and effectually retained in position, and which will furthermore possess advantages in point of convenience, ease of operation, adjustability, effectiveness, and general efficiency.

In the drawings, Figure 1 is a perspective view showing the screen in raised position. Fig. 2 is an end or edge elevation. Fig. 3 is a detail vertical sectional view taken on the line 1 1, Fig. 1. Fig. 4 is a detail vertical sectional view taken on the line 2 2, Fig. 1. Fig. 5 is a detail perspective view illustrating the arrangement and operation of the side retaining-strips. Fig. 6 is a detail horizontal sectional view taken on the line 3 3, Fig. 1, showing the screen fabric clamped in position. Fig. 7 is a corresponding view illustrating the passage of the side extensions of the top strip with relation to the side securing-strips. Fig. 8 is a detail horizontal sectional view taken on the line 4 4, Fig. 1. Fig. 9 is a transverse horizontal sectional view taken on the line 5 5, Fig. 1.

Referring to the drawings, A designates the window frame or casing, and B the lower sash of the same.

C designates a spring-actuated roller mounted at the lower end upon the window sill or face of the casing and carrying the flexible screen fabric D.

The screen fabric D is extended at its side edges, as shown at d d, so that it will project

over the face a a of the window frame or casing A, the relative width or transverse size of the screen being thus greater than the window-opening. At its top the edge d' is bound between the inner and outer members E' and E², respectively, of a top strip E. The strips E' and E² are securely fastened or bound together. The top strip E thus carries the upper edge of the screen fabric and extends transversely and horizontally across the window, the inner member or strip E' being of a length corresponding to the space between the vertical side beads a' a' of the window-frame and traveling between the same, while the outer member or strip E² is extended at its ends, as shown at e² e², so that it corresponds in width to the screen fabric D and has its ends e² e² projecting over the face of the window-frame.

Upon the top strip E are provided screw-eyes f f, projecting vertically and adapted to be engaged by hooks g g, provided upon the bottom stile or cross-piece b of the sash. These hooks are preferably pivotally mounted, so that they will rest in flat position with relation to the sash and swing in a longitudinal plane with relation to the cross-bar b, while the screw-eyes f are preferably relatively mounted in transverse position with relation to the line of travel of the screen. Upon the top strip E is also preferably provided a projecting knob h, by which the screen may be raised or manipulated to effect the connection of the screw-eyes f with the hooks g.

I designates side strips of suitable length mounted in vertical position upon the face a a of the window frame or casing and with relation to the side edges d d of the screen, which project over the face of the window frame or casing. These strips are adapted to move inwardly and outwardly with relation to the face a a of the window-casing to permit the passage of the projecting ends e² e² of the outer member or strip E² of the top strip E between said movable binding-strips I I and the face of the window-casing in the adjustment of the screen, and also to enable the clamping or binding of the projecting side edges d d of the screen between said binding-strips I I and the face of the window-casing

when the screen is in adjusted position. In thus mounting the movable side binding-strips I I upon the face *a a* of the window-casing I prefer to provide said strips at their 5 upper and lower ends with openings or perforations *i*, through which pass headed pins or nails *J*, horizontally arranged and projecting from the face of the window-casing, the binding-strips being thus mounted and adapt- 10 ed to slide upon said headed pins and the latter being of sufficient length to permit the proper sliding movement of the strips. When the binding-strips I I are at their outward limit of movement, the projecting ends *e² e²* 15 of the top strip will pass readily between the binding-strips and the face of the window-casing, and when the screen is in adjusted position the binding-strips are pushed in so that they will securely bind or clamp the free 20 projecting side edges *d d* of the screen fabric or netting against the face of the window-casing.

To retain the strips I I in binding or clamp- 25 ing position, I provide suitable thumb-buttons or clamps *J'*, pivotally mounted with relation to the strips and adapted to be turned to securely clamp the strips against the face of the window-casing.

The operation and advantages of my inven- 30 tion will be readily understood.

By reason of my improved construction and arrangement of parts, the objection usually experienced in flexible rolling window-screens of this class pulling out from edge guides and 35 bellying at the center in stormy weather is effectually obviated. The projection of the side edges of the flexible screen-netting over the face of the window-casing and the clamp- 40 ing of the same against the face of the casing by the movable side binding-strips, in connection with the general construction and arrangement of parts as embodied in my inven- 45 tion, provides an effective screen of this type in which the side edges of the flexible screen fabric are securely bound or retained in position against the face of the window-casing.

By reason of the improved construction and arrangement of parts as embodied in my invention, it will be noted that the screen can 50 be lowered or raised and adjusted independ- 55 ent of the sash, or the sash and screen can be operated together in the usual manner.

Having thus described my invention, I claim and desire to secure by Letters Pat- 55 ent—

1. An improved rolling window-screen of

the class described, comprising, in combina- 60 tion with the window frame or casing and the sash, the flexible rolling-screen fabric having the extended side edges *d d* projecting over the 65 face of the window-casing, the top strip embodying the inner member or strip adapted to operate between the sides of the window- casing and the outer member or strip having the extended ends *e² e²* projecting over the 70 face of the window-casing and corresponding to the projecting side edges *d d* of the screen fabric, the screw-eyes upon said top strip and the engaging hooks upon the sash, and the vertical movable side strips mounted upon 75 the face of the window-casing and adapted to slide upon the headed pins projecting there- from, said side strips being adapted to move inwardly and outwardly with relation to the face of the window-casing to clamp or bind 80 the projecting edges *d d* of the screen fabric against the face of the casing, the casing being provided with thumb-buttons for clamp- 85 ing the strips in position, substantially as and for the purpose set forth.

2. The herein-described improved rolling window-screen, comprising, in combination with the window frame or casing and the sash, the flexible screen fabric *D* having the extended side edges *d d* projecting over the 85 face of the window-casing, the spring-actuated roller *C* to which the lower end of the screen fabric is secured, the top strip *E* embodying the inner strip or member *E'* adapted to operate between the sides of the window-casing 90 and the outer strip or member *E''* having the extended ends *e² e²* projecting over the face of the window-casing and corresponding to the extended side edges *d* of the screen fabric, the screw-eyes upon said top strip and the en- 95 gaging hooks upon the sash, the vertically- mounted clamping-strips I adapted to move inwardly and outwardly with relation to the face of the window-casing upon the headed pins *J* projecting from the casing, and the thumb- 100 buttons *J'* for clamping said movable strips against the face of the casing, said binding- strips being adapted to clamp or bind the projecting side edges of the screen fabric against the face of the window-casing, sub- 105 stantially as and for the purpose set forth.

In testimony whereof I affix my signature in presence of two witnesses.

SAMUEL H. CASSELBERRY.
